WALTER S. WARD AND ALBERT MAXIM, OF NEW YORK, N. Y., ASSIGNORS TO WARD BAKING COMPANY, OF NEW YORK, N. Y., A CORPORATION OF NEW YORK.

AUXILIARY AIR-SUPPLY DEVICE.

1,256,082.

Specification of Letters Patent. Patented Feb. 12, 1918.

Application filed August 19, 1913. Serial No. 785,499.

To all whom it may concern:

Be it known that we, WALTER S. WARD, a citizen of the United States, residing in New York city, county and State of New York, whose post-office address is Southern Boulevard and East 143 St., New York, N. Y., and ALBERT MAXIM, a citizen of the United States, residing in New York city, county and State of New York, and whose post-office address is 715 Union Ave., Bronx county, New York, N. Y., have invented certain new and useful Improvements in Auxiliary Air-Supply Devices for Internal-Combustion Engines; and we do hereby declare the following to be a full, clear, and exact description of the invention, such as will enable others skilled in the art to which it appertains to make and use the same.

The invention relates to internal combustion engine control and consists in providing means whereby the operation of a throttle operating member after a preliminary period of operation in which it opens the throttle of the engine to an extent required for low speeds is caused during its continued movement to open a valve in a supplemental air intake conduit located in proximity to a hot part of the engine and admit heated uncARBURATED air to the intake manifold of the engine beyond the throttle in order to completely vaporize any wet gasolene which is past the throttle before its admission to the engine cylinders.

Upon starting and while the engine is running slowly, a somewhat rich mixture is desired, but little cold is produced in the intake manifold and consequently little condensation of the gasolene is effected. During this starting and slow speed period, the admission of supplemental air to the intake manifold is undesired in view of its diluting action upon the gasolene; but when high speed of the engine is reached the rapid vaporization of the gasolene in the mixing chamber of the carbureter produces an extreme cold, which causes a condensation of the gasolene in the intake manifold immediately beyond the throttle, and it is extremely advantageous when the period of high speed is reached to permit warmed air to enter the intake manifold just beyond the throttle and counteract the condensation of the gasolene, the added heat making up for the lowering of the temperature by quick

vaporization and producing the proper attenuation of the mixture for high speeds.

It has been proposed to admit comparatively warm air at the point named to accomplish the desirable result just described, but the skill and judgment of the operator has been depended on to determine the time at which the supplemental warmed air should be admitted, the operation of a valve in the supplemental air conduit by hand having been depended on.

We have removed the personal equation from the operation of the supplemental air conduit, and rendered its operation automatic in conjunction with the operation of the throttle, the admission of the supplemental air being positively controlled by the speed of the engine.

We have illustrated an embodiment of the present invention in the accompanying drawings, in which

Figure 1, is a side elevation of a four cylinder engine showing intake and exhaust manifolds, carbureter, throttle, the supplemental air conduit, its valve, and mechanism whereby the operation of the supplemental air conduit valve is dependent upon the operation of the throttle operating member.

Fig. 2, is a vertical section on line 2—2 of Fig. 1. Fig. 3 is a perspective view of the curl Q, which engages the crank of the valve K.

Referring to the drawings, the engine A is shown provided with the intake manifold B. The stem C of the throttle mounted in the upper part of the carbureter D is provided with a crank E to which a throttle-operating rod F is pivoted at f. A movement of the rod F to the right from the position shown in Fig. 1 opens the throttle and admits carbureted air from the carbureter D through a mixing chamber G to the intake manifold B of the engine A. A pipe H has one end tapped into the intake manifold B above or beyond the throttle C, the other end of the pipe H being coiled about the exhaust manifold J of the engine. A valve K is interposed in the pipe H and upon its stem k is rigidly mounted a crank L, shown in the drawing in a position held against a stop pin M by a spring N in which position of the crank L the valve is closed precluding the passage of supplemental air through the pipe H to the intake manifold

B. The throttle operating rod F is threaded to accommodate two lock nuts O, O between which a bracket P is adjustably secured upon the rod F. The bracket P is provided with a curl at Q, which after a certain movement of the rod F toward the right, dependent upon the position upon said rod to which the bracket P has been adjusted, will engage with the crank L of the valve K, a further movement of the rod F to the right moving the crank L and opening the valve K, permitting supplemental air to be drawn into the pipe H and there heated in its passage about the exhaust manifold J of the engine, and thence into the intake manifold B. When the rod F is retracted toward the left in Fig. 1, the retrograde movement of the bracket P permits the spring N to return the crank L and close the valve K, the curl Q on the bracket P leaving the crank L against its stop pin M, and moving away therefrom during the completion of the throttling down movement. To avoid a possible sticking of the valve K and failure of the spring N to return the same to the closed position, a loop R is bent upon the bracket P to engage a pin S upon the crank L during the retrograde movement of the rod F, which action will insure the closure of the valve K. Ample room is provided within the loop R for the proper operation of the various parts.

The operation of the device is as follows: When the engine is started, the throttle operating member or rod F is in, or but slightly removed from, the position shown in Fig. 1, and the throttle C is but slightly open and a considerable motion of the rod F toward the right in Fig. 1 can take place farther opening throttle C and producing the lower speeds of the engine before the curl Q on the bracket P engages the crank L of the valve K. This is the preliminary period of low speeds during which no supplemental air should be admitted to the intake B of the engine, and during this period the valve K is closed. The range of operation of the throttle during this period may

be diminished or extended by adjusting the bracket P to the right or the left respectively on the rod F. When the engine has attained a speed where the suction through the intake B is sufficient to lower the temperature of the incoming gasoline to a point where condensation of the gases in the intake occurs, or when wet gasoline is present in the intake, the position of the throttle operating rod F will be such as to cause the bracket P to open the valve K by the movement of the crank L by the curl Q upon the bracket P, and the suction in the intake will cause air to enter the pipe H and therein be heated in passing about the exhaust manifold J, the heated air finally being drawn into the intake manifold B, where it effects complete vaporization of the wet gasoline, thereby increasing the output of the engine 20 or 30 per cent. without calling for any additional operating skill on the part of the operator.

What we claim is:—

The combination of intake and exhaust conduits for an internal combustion engine, a throttle governing the supply of carbureted air to said intake conduit, a supplemental air intake conduit wrapped around said exhaust conduit and heated thereby, said supplemental intake conduit being arranged to supply heated air to said intake conduit beyond said throttle, a valve governing the supply of said supplemental air, means for opening and closing the throttle, a crank connected with said valve and a bracket adjustably connected with said throttle operating means and coming into operative engagement with said crank subsequent to a predetermined preliminary opening movement of said throttle; substantially as described.

In testimony whereof we affix our signatures, in presence of two witnesses.

WALTER S. WARD.
ALBERT MAXIM.
